CLAIM

The ornamental design for a fluorescent nucleic acid probe detection cartridge assembly unit, as shown and described.

DESCRIPTION

FIG. 1 is a top view of a fluorescent nucleic acid probe detection cartridge assembly unit showing the cover separated from the assembly for clarity of disclosure

FIG. 2 is a top perspective view of a fluorescent nucleic acid probe detection cartridge assembly unit showing the cover separated from the assembly for clarity of disclosure

FIG. 3 is a side view of a fluorescent nucleic acid probe detection cartridge assembly unit showing the cover separated from the assembly for clarity of disclosure

FIG. 4 is a side view of the fluorescent nucleic acid probe detection cartridge assembly unit showing the cover separated from the assembly for clarity of disclosure

FIG. 5 is a bottom view of a fluorescent nucleic acid probe detection cartridge assembly unit showing the cover separated from the assembly for clarity of disclosure.

FIG. 6 is a bottom perspective view of a fluorescent nucleic acid probe detection cartridge assembly unit showing the cover separated from the assembly for clarity of disclosure

FIG. 7 is a fluorescent nucleic acid probe detection cartridge assembly unit showing the top view of the inner layer separated from the assembly for clarity of disclosure

FIG. 8 is a fluorescent nucleic acid probe detection cartridge assembly unit showing the bottom view of the inner layer separated from the assembly for clarity of disclosure; and,

FIG. 9 is an exploded view of a fluorescent nucleic acid probe detection cartridge assembly unit of FIG. 1.
